US0D1089023S

(12) **United States Design Patent** (10) Patent No.: **US D1,089,023 S**
(45) Date of Patent: ** Aug. 19, 2025

(54) **TAILGATE PANEL FOR AN AUTOMOBILE**

(71) Applicants: **Hyundai Motor Company**, Seoul (KR); **Kia Corporation**, Seoul (KR)

(72) Inventors: **Geon Hee Lee**, Seoul (KR); **Ji Hoon Seol**, Hwaseong-si (KR)

(73) Assignees: **Hyundai Motor Company**, Seoul (KR); **Kia Corporation**, Seoul, Republic of (KR)

(**) Term: **15 Years**

(21) Appl. No.: **35/521,398**

(22) Filed: **Dec. 21, 2023**

(80) **Hague Agreement Data**

Int. Filing Date: **Dec. 21, 2023**

Int. Reg. No.: **DM/234325**

Int. Reg. Date: **Dec. 21, 2023**

Int. Reg. Pub. Date: **Jun. 21, 2024**
